CLAIM

The ornamental design for a button for a shaving razor, as shown and described.

DESCRIPTION

FIG. 1 is a front, top, perspective view of a button for a shaving razor showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front, bottom, perspective view thereof; and,

FIG. 9 is a rear perspective view thereof.

In the drawings, the broken line triangular feature on the top surface of the button illustrates a portion of the article which form no part of the claimed design. The remaining broken lines illustrate environmental subject matter and form no part of the claimed design.

1 Claim, 6 Drawing Sheets(56)
